(57) **CLAIM**

The ornamental design for cabinet handles, as shown and described.

DESCRIPTION

FIG. 1 is a perspective view of a cabinet handle showing our new design;

FIG. 2 is a perspective view of a second embodiment of a cabinet handle showing our new design, the only difference being the length;

FIG. 3 is a perspective view of a third handle.

FIG. 4 is a top view of the handle shown in FIG. 1.

FIG. 5 is a front view of the handle shown FIG. 1.

FIG. 6 is a top view of the handle shown in FIG. 2.

FIG. 7 is a front view of the handle shown in FIG. 2.

FIG. 8 is a side view of the handle shown in FIG. 3.

FIG. 9 is a front view of the handle shown in FIG. 3.

FIG. 10 is a bottom view of the handle shown in FIG. 3.

FIG. 11 is a cross section of the base portion of the handle shown in FIG. 8, taken along lines 11-11 shown in FIG. 8; and,

FIG. 12 is a cross section of the handle portion of the handle shown in FIG. 8, taken along lines 12-12 shown in FIG. 8.

Portions of FIGS. 1-12 that are shown as broken lines are for illustrative purposes only and form no part of the claimed design.
